UNITED STATES PATENT OFFICE.

FRANK J. DUX, OF UTICA, NEW YORK.

ARMHOLE BEAD FOR GARMENTS.

Application filed March 15, 1927. Serial No. 175,564.

My invention relates to an armhole bead for garments and I declare the following to be a full, clear, concise and exact description thereof sufficient to enable anyone skilled in the art to which it appertains to make and use the same, reference being had to the accompanying drawings in which like reference characters refer to like parts throughout the specifications.

10 The object of the invention is to form a positive break line in the lowermost part of the armhole of a garment, and to protect the sleeve and body lining of the garment from wear as well as to effect a more perfect fitting coat, as hereinafter explained. To this end, there is employed a bead which is made by folding along the longitudinal center a tape and enclosing in the fold a cord that will not stretch. The tape is made of 20 a fabric material that will stretch slightly. This is sewed to the garment in such manner as to extend from about the middle of the back of the armhole to about the middle of the front thereof. At the terminal points 25 it will be anchored by stitching by hand or machine. Although the bead, as just stated, extends only about the lower half of the armhole, it may be continuous for the whole way round, the upper half being merely 30 ornamental or forming sort of binding edge to armhole sleeve lining.

The tape is sewed or seamed so as to be snug under the armhole. To this end it will cover a little more than its own distance 35 from the middle of the back of armhole to about the middle of the front thereof thereby causing the bead or folded part of the tape to be the shortest member of the materials, sewed together and faced towards the 40 shortest radius around the armhole, after the lower half of armhole seam has been pressed over into sleeve. The bead being therefore at the peak of the armhole or junction between sleeve and coat, will effect a 45 line of demarkation at the bottom of armhole as well as a guide to fell or sew sleeve lining to at the top of the armhole. As stated above, the bead will not stretch, although the sewed part of the tape will to a 50 limited extent. This construction will cause all the other materials of the garment to hang or be suspended from the bead, which construction will prevent the materials of the garment below the armhole from sagging, balling or rolling and effect a more 55 perfect chest to the garment, thereby en-

hancing its general appearance both on the inside and outside. Inasmuch as the bead is sewed to the armhole part of the garment in such manner as to cover more distance 60 around armhole than its own length, being held especially short or snug around lower half of armhole; that is by being held short, I mean, that the cloth to which the bead is sewed is filled in while bead is held tight, 65 whereby especially at the lower half of front of the armhole said bead will cover more than its own length than that of the materials to which it is sewed, whereby it will tend to draw together the cloth forming the 70 chest part at the front of the armhole, to effect a more perfect chest. The armhole seam will be pressed over or broken along its lower half and its upper half lie flat as is customary in making coats, whereby the bead 75 will be held in the center between sleeve and coat part of the armhole and being the shortest of the materials that go to form the armhole will naturally have a tendency to remain so positioned.

80 The object will be understood by referring to the drawings in which:

Fig. 1 is a fragmentary view of a coat looking at the inside lining thereof and showing the novel armhole construction.

85 Fig. 2 is a side elevation of a vest showing the novel armhole construction applied thereto.

Fig. 3 is a detail enlarged view of the bead employed.

90 Fig. 4 is a detail enlarged view partly in section and partly broken away showing the arrangement of the bead with respect to the fabric and trim of the garment.

95 Fig. 5 is a side view of the forepart of a vest showing bead and container applied thereto and before sewed to lining and turned right side out and the back part of the vest removed.

100 Fig. 6 is a side view of the forepart of the vest showing bead and container applied thereto, parts being broken away.

Fig. 7 is a side view of the forepart of the vest showing location of bead and container in the garment after the proper sewing and placing of lining, back part of vest being removed.

105 Fig. 8 is a view of the vest showing the inside of same laid against the outside and with back part of vest removed and bead 110 and container applied in position.

Referring more particularly to the draw-

ings, a garment suit as a coat shown in Fig. 1 or a vest as in Fig. 2 is represented by 1 and 1^a respectively. In the case of coat 1 there will be the usual sleeve 2. In making coat 1 there will be the outer material 5, canvas 6, felt padding 7 and the inside lining 8 disposed in successive layers from outside to inside of the coat in the order named. Likewise, the sleeve has the outside material 10 of same pattern as material 5 of the coat, and inside lining 12.

The cloth 5 of the coat, and the cloth 10 of the sleeve are folded back along their respective edges and seamed together at the 15 location of the armhole 11 and continuously around armhole, thereby sewing sleeve 2 and coat 1 together. Thereupon, canvas 6, padding 7 and lining 8 of coat 1 are basted around armhole 11 and to outside material 20 or cloth 5 and fastened to armhole seam 12^a of coat 1 and sleeve 2 by hand stitching, which is called ordinarily in the art, serging. After the outside material 5 of coat 1 and inner trim comprising canvas 6, felt padding 7 and lining 8 thereof are basted together and the armhole serged or hand stitched, bead 13 is applied. As before stated, bead 13 is formed by folding along its longitudinal center a tape 14 and enclosing in the folded part a cord 15, or the bead may be formed by cutting a piece of material on the bias, folding it longitudinally with the cord disposed in the folded part and then stitching said cord firmly between the 35 folded part of the material. The cord and material will be stitched together or fastened in any suitable way as by weaving, whereby to effect an edge contiguous with the cord that will not stretch and an opposite part that will stretch or give slightly on the other. Tape 14 will be sewed along line indicated at 14^a and adjacent bead 13 to armhole 11. The stitches will go through tape 14, lining 8, felt padding 7, canvas 6 40 and outside material 10 of sleeve and outside material 5 of coat. Tape 14 is sewed in such manner that bead 13 will be parallel with the seam 12^a formed at the junction of coat 1 and sleeve 2 at armhole 11. However, 45 canvas 6, padding 7 and lining 8 will be between tape 14 and armhole seam 12^a of coat and sleeve. Sleeve lining 12 is felled or sewed into place next adjacent tape 14.

As stated above, tape 14 will stretch to a 55 slight degree and the folded part 16 containing cord 15 will not stretch. This latter part extends or projects into the armhole 11 at the junction of the coat and sleeve lining.

60 The part 16 of the tape 14 containing cord 15 will be anchored at diametrically opposite parts of the armhole as at 20, 20 by stitching by hand or machine. Moreover, part 16 containing cord 15 will be sewed in a snug manner under the armhole as at 21,

that is, by slightly or almost imperceptibly pleating the material to which tape 14 is sewed, whereby cord 15 will cover slightly more of the material than its own length. Especially will tape 14 be sewed snug, tight 70 or short in front of the armhole from the scye or pit of armhole as at 23 to a point 24 within approximately three inches above front notch 25, whereby cord 15 will aid in providing fullness in front to form the chest 75 26 of the garment. Furthermore, the tightness of cord 15 will prevent the material at the lower part of armhole from sagging or balling. On the other hand, said materials will be suspended from bead or cord 15 to thereby enhance the appearance of the garment.

Fig. 8 shows the stitches 30 which are sewed adjacent bead 13 thereby fastening tape 14 in proper position between outside 85 material 5 and lining 8 of the vest.

Having thus described my invention, what I claim as new and desire to secure by Letters Patent, is as follows:

1. In an armhole bead for garments having a sleeve portion and a chest portion, an armhole at the junction of said portion and a cord sewed adjacent said armhole, whereby to aid in forming a chest portion of the garment.

2. In an armhole bead for garments having a sleeve portion and a chest portion with an armhole, an unyielding cord sewed under said armhole whereby to aid in forming and supporting the chest portion of the garment.

3. In an armhole bead for garments having a sleeve portion and a chest portion with an armhole therebetween, a tape member enclosing a cord sewed adjacent said armhole, whereby to aid in forming and supporting said chest portion.

4. In an armhole bead for garments having a sleeve portion and a chest portion, and an armhole at the junction of said portions, 110 said sleeve comprises an outside material and an inner trim and said chest portion comprises an outside material and an inner trim and an unyielding cord fastened adjacent the junction of said sleeve and chest portions, whereby to aid in supporting said chest portion.

5. In an armhole bead for garments having a sleeve portion and a chest portion, an armhole at the junction of said portions, 120 said sleeve comprising an outside material and an inner trim and said chest portion comprising an outside material and inner trim and a folded tape containing a cord fastened adjacent the junction of said 125 sleeve and chest portions, whereby to aid in supporting said chest portion.

In testimony whereof I affix my signature.

FRANK J. DUX.
